UNITED STATES PATENT OFFICE

2,532,732

MECHANICAL HAND

Thomas B. Sansbury, Orlando, Fla.

Application February 6, 1948, Serial No. 6,741

4 Claims. (Cl. 3—12)

1

This invention relates to prosthetic apparatus and has special reference to an artificial hand.

One important object of this invention is to provide a novel construction of artificial hand.

Another important object of this invention is to provide an artificial hand having two claws or fingers especially designed in a novel manner to ensure a firm grip on any article grasped by the hand.

A further object of this invention is to provide a novel hook-like artificial hand wherein the fingers will positively lock an object without the necessity of manipulating a locking mechanism by the other hand.

Still another object of the invention is to provide a novel construction of artificial hand wherein no ratchet or other like lock exists and wherein a single control wire is all that is used for opening the fingers.

Yet another object of the invention is to provide a novel shape of claw or finger so formed as to facilitate the gripping of an automobile gear shift, the grasping of a steering wheel and steering with it, the openings of doors, and securely holding table utensils, screw drivers, hand saws and many other articles.

With the above and other objects in view, as will be presently apparent, the invention consists in general of certain novel details of construction and combinations of parts hereinafter fully described, illustrated in the accompanying drawings, and particularly claimed.

In the drawings, like characters of reference indicate like parts in the several views, and

Figure 1 is a plan view of the device with one of the casing covers removed;

Figure 2 is a view from the right side of Figure 1, the view being partly in section;

Figure 3 is a detail section on the line 3—3 of Figure 1;

Figure 4 is a detail section on the line 4—4 of Figure 1;

Figure 5 is a view partly in elevation and partly in section and showing the manner of attaching the hand to an arm socket;

Figure 6 is a view partly in elevation and partly in section and showing the manner of immovably securing one of the fingers; and

Figure 7 is a view from the top of Figure 1 but showing only certain portions of the fingers.

In the construction of the invention as here shown, there is provided a body 10 of general U-shape and from the base of the U there extends a threaded lug 11 for attaching the device to a socket adapted to be fitted on the stump of an amputated arm.

On each side of this body 10 is a plate 12 having a centrally disposed H-shaped opening 13, the opening extending transversely of the body and thus having its wider portions adjacent the arms

2

of the U. For the purpose of describing the relative positions and shapes of certain of the parts of this device, the axis of the member 11 is to be considered as the central axis of the hand. To avoid confusion, the parts to the right and left of Figure 1 will be so referred to, while those parts extending back from Figure 1 will be considered as extending or located rearwardly of this imaginary axis.

On the right leg of the body 10 a rabbet 14 is formed. At 15 is a fixed arm, this arm having a rabbet 16 which overlaps with and fits in the rabbet 14. A screw 17 passes through the overlapping portions of the rabbets and firmly connects them. A bolt 18 also connects the front plate 12 with the arm 15 so that the arm is held rigid against movement in any direction.

Extending between the arms of the U-shaped body 10 is a shaft 19. On this shaft is rotatably mounted an operating member having a drum 20 at one end and a cylindrical opposite end 21. Between the ends 20 and 21 the operating member is formed as a deeply grooved screw 22. Extending between the plates 12 is a pivot bolt 23 whereon is pivoted a movable arm 24. This arm 24 has a nose 25 which engages in the groove of the screw 22 so that rotation of this screw effects biasing movement of the arm 24.

The arms 15 and 24 are reversely curved so as to present arcuate bends 26 with their concave sides confronting and with the outer ends of these bends substantially in contact. The terminal portions of the arms 15 and 24 are bent rearwardly to form fingers 27, as best seen in Figure 2. The fingers 27 have arcuate bends 28, the concave sides of which are in opposition, thus enabling anything gripped by the fingers to be securely held. Around the drum 20 is wound a cord of cable 29 which passes through a suitable opening in the base of the body and carries on its free end a connector 30 for the operating wire (not shown). When tension is exerted on this cable, the screw 22 is rotated. Fixed to and wound spirally about the end 21 is a spring 31 which extends along the rear plate 12 and has its end secured thereto by a screw 32. The spring 31 constantly tends to rotate the screw 22 in such direction that the nose 25 moves to the left and the arm 24 thus tends to close on the arm 15. The cable 29, when sufficient tension is brought thereon, will rotate the screw 22 in the opposite direction against the action of said spring and thus cause movement of the movable arm 24 away from the fixed arm 15 as indicated by the broken lines in Figure 1.

In Figure 5 there is shown a sleeve 33 for covering the stump of an amputated arm and provided with a metallic cuff end 34 through which the screw 11 projects and is there secured as shown at 35.

Covering caps 36 are secured to the plates 12 to protect the operating mechanism and to render the device attractive in appearance.

What is claimed is:

1. In an artificial hand, a body, an article-gripping arm immovably fixed to said body, a second arm pivotally mounted intermediate its ends on said body and movable toward and from the fixed arm, said second arm having an outwardly extending article-gripping portion and a second portion extending inwardly of said body, an operating screw extending transversely of said body, a nose on the second portion of said second arm directly engaging said screw, said screw being elongated and of less diameter in its center than at its ends and presenting a concavely arcuate pitch surface, and means to rotate said screw in each direction.

2. In an artificial hand, a body, an article-gripping arm immovably fixed to said body, a second arm pivotally mounted intermediate its ends on said body and movable toward and from the fixed arm, said second arm having an outwardly extending article-gripping portion and a second portion extending inwardly of said body, an operating screw extending transversely of said body, a nose on the second portion of said second arm directly engaging said screw, said screw being elongated and of less diameter in its center than at its ends and presenting a concavely arcuate pitch surface, an operating cord arranged to rotate the screw in one direction, and a spring urging the screw in the opposite direction.

3. In an artificial hand, a body, an article-gripping arm immovably fixed to said body, a second arm pivotally mounted intermediate its ends on said body and movable toward and from the fixed arm, said second arm having an outwardly extending article-gripping portion and a second portion extending inwardly of said body, an operating screw extending transversely of said body, a nose on the second portion of said second arm directly engaging said screw, said screw being elongated and of less diameter in its center

than at its ends and presenting a concavely arcuate pitch surface, a drum at one end of said screw, a cord wound around said drum and rotating the drum and screw in one direction upon the cord being drawn off the drum, and spring means urging the drum and screw in the opposite direction.

5 4. In an artificial hand, a body, an article-gripping arm immovably fixed to said body, a second arm pivotally mounted intermediate its ends on said body and movable toward and from the fixed arm, said second arm having an outwardly extending article-gripping portion and a second portion extending inwardly of said body, an operating screw extending transversely of said body, a nose on the second portion of said second arm directly engaging said screw, said screw being elongated and of less diameter in its center than at its ends and presenting a concavely arcuate pitch surface, a drum at one end of said screw, a cord wound around said drum and rotating the drum and screw in one direction upon the cord being drawn off the drum, a cylinder at the end of the screw remote from the drum, and a spring coiled around said cylinder in a direction opposite the winding of said cable and having one end fixed to said body.

THOMAS B. SANSBURY.
